Primary Examiner — Carol P Rademaker*(74) Attorney, Agent, or Firm* — Mark J. Nahnsen; Barnes & Thornburg LLP**CLAIM**

The ornamental design for a bottle, as shown and described.

DESCRIPTION

FIG. 1 is a top, front isometric view of a bottle;

FIG. 2 is a rear elevational view thereof;

FIG. 3 is a front elevational view thereof;

FIG. 4 is left side view thereof;

FIG. 5 is right side view thereof;

FIG. 6 is a top plan view thereof; and,

FIG. 7 is a bottom plan view thereof.

The broken lines shown in the drawing views are included for the purpose of illustrating environmental structure and form no part of the claimed design.
